WELL CLEANER

Charles K. Holt, Bakersfield, Calif.

Application January 3, 1939, Serial No. 248,915

16 Claims. (Cl. 166—20)

This invention relates to a well tool and relates more particularly to a well cleaner or perforation cleaner. A general object of the invention is to provide a simple, practical and effective

5 tool for cleaning the perforations of well liners.

Tools known as well cleaners or perforation cleaners are employed to remove accumulated matter and obstructions from the perforations of well liners to increase the production of the wells.

10 A typical well cleaner or perforation cleaner embodies vertically spaced packers for engaging in the well liner, and pump means for forcing fluid between the packers to discharge outwardly through perforations of the liner to clean the same. Such cleaners are not altogether satisfactory as they do not clean all of the perforations of the liner. Frequently a few of the perforations of the liner located in the zone between the packers of the cleaner will be clear or free of 15 obstructions, and the fluid under pressure forced between the packers flows through these open perforations and does not clean the clogged perforations.

Another object of this invention is to provide 20 a well cleaner that is operable to fully clean all of the perforations of a well liner to greatly increase the production of the well.

Another object of this invention is to provide 25 a well cleaner that operates to concentrate the discharge of the fluid under pressure at a few of the perforations of the liner to fully clean the same of all obstructions.

Another object of this invention is to provide 30 a well cleaner that embodies a novel packer having a discharge orifice of limited area for concentrating the discharge of the fluid under pressure to flush through a limited number of perforations of the liner to fully clean the same.

Another object of this invention is to provide 35 a well cleaner of the character mentioned in which the packer is shifted vertically or is left stationary while the fluid is discharged under pressure from its discharge orifice so that the perforations of a vertically extending band or of a given

40 zone of the liner are fully cleaned during one phase of operation of the tool. In one manner of operating the cleaner provided by this invention the fluid discharging packer may be moved longitudinally in the liner as the fluid is discharged through the perforations to fully clean the perforations throughout a vertically extending zone or area and this operation is followed by a partial turning of the packer and a repeated 45 vertical movement of the packer accompanied by the discharge of the fluid under pressure so

that a second and contiguous vertical zone of the liner is cleaned and this series of operations may be repeated until the entire liner is thoroughly cleaned.

Another object of this invention is to provide 5 a well cleaner of the character mentioned in which the packer effectively seals with the liner around the fluid discharge orifice of the packer to assure the full discharge of the fluid under pressure at the limited zone of the liner opposite the orifice. 10

Another object of this invention is to provide 15 a well cleaner of the character referred to in which the packer is carried by the reciprocating element of the pump means to move vertically in the liner during the fluid ejecting and perforation washing operation.

Another object of this invention is to provide 20 a novel fluid discharging packer for use on a well cleaner, or the like.

The various objects and features of my invention will be fully understood from the following 25 detailed description of typical preferred forms and applications of the invention, throughout which description reference is made to the accompanying drawing, in which:

Fig. 1 is a side elevation of one embodiment of the invention showing the tool in the operative position in a well liner and illustrating the liner in longitudinal cross section. Fig. 2 is an enlarged longitudinal detailed sectional view of the 30 pump means and anchor means showing the anchor means in a retracted condition and illustrating certain parts in side elevation. Fig. 3 is an enlarged horizontal detailed sectional view of the packer illustrated in Fig. 1, being a view 35 taken in a plane through the discharge orifice. Fig. 4 is a longitudinal detailed sectional view of the packer illustrated in Fig. 1 being a view taken in a plane extending through the discharge orifice and illustrating certain parts in elevation, 40 and Fig. 5 is an enlarged fragmentary longitudinal detailed sectional view of another form of packer provided by the invention.

The embodiment of the present invention illustrated in Figs. 1 to 4, inclusive, of the drawing 45 includes, generally, pump means 10, means 11 for releasably anchoring or securing the pump means 10 in a well liner L, a packer 12 carried by the pump means 10 and operable to discharge the pumped fluid through the perforations P of the 50 liner L, and a swab element 60 carried by the pump means and operable in the liner L.

The pump means 10 is adapted to be entered in the well liner L and to be releasably anchored or secured in a selected position in the liner by the 55

means 11. The pump means 10 is preferably a barrel and plunger means operable by a reciprocable well string S. In the construction illustrated the pump means 10 includes a barrel 13 to be anchored in the liner L and a plunger 14 operable in the barrel. The barrel 13 is an elongate tubular member provided at its opposite ends with threaded-on heads or caps 15. The upper portion of the pump barrel 13 has communication with the interior of the liner L. In the typical arrangement illustrated ports 16 are provided in the upper cap 15 to put the interior of the barrel 10 in communication with the liner L.

The plunger 14 of the pump means 10 is connected with the well string S to be reciprocated and turned thereby. The plunger 14 shiftably passes through an opening 17 in the lower cap 15 and the said lower cap carries a packing gland 18 for sealing about the plunger. A head 19 is provided on the upper end of the plunger 14 to shiftably operate in the pump barrel 13. The well string S extends through an opening 20 in the upper barrel cap 15 and is sealed about by a gland 21 on the upper cap. A connection is provided between the string S and the plunger head 19 whereby the plunger may be reciprocated by the string S. In the case illustrated the lower end of the string S is threaded in a socket 22 in a plug 23 which in turn is threaded in a socket 24 in the upper end of the head 19.

Valve means are associated with the plunger head 19 so that reciprocation of the plunger 14 in the barrel 13 produces a pumping action. The valve means of the plunger 14 may take various forms. The string S may be ported and placed in communication with the inner portion of the socket 24 or the plug 23 may be ported to act as an inlet member. In the construction illustrated ports 25 are provided in the plug 23 to place the inner portion of the socket 24 in communication with the upper end part of the barrel 13 and ports 26 extend through the head 19 from the socket 24 to put the socket in communication with the portion of the pump chamber below the head. An annular valve 27 is provided in the socket 24 and is adapted to seat up against the lower end of the plug 23 to close the ports 25. A ring 28 is arranged in the socket 24 and carries springs 29 for urging the valve 27 to its closed position against the plug 23. During the up stroke of the plunger 14 a reduced pressure is created in the barrel 13 below the head 19 and the valve 27 opens to allow fluid from the liner L to pass through the ports 25 and 26 into the pump chamber below the head 19. During the down stroke of the plunger 14 the valve 27 is closed against the lower end of the plug 23 to prevent the discharge of fluid through the ports 25.

A central vertical opening 30 extends into the head 19 from its lower end to communicate with the socket 24. The upper end of the plunger 14 is threaded in the lower part of the opening 30. The pump plunger 14 is tubular having a central longitudinal opening 31 and this opening is in communication with the opening 30 in the head 19. A valve is provided to control communication between the plunger opening 31 and the portion of the barrel pump chamber below the head 19. An annular downwardly facing seat 32 is provided on the wall of the opening 30 and a ball valve 33 is arranged in the opening 30 to seal upwardly against the seat 32. A ring 35 is threaded in the opening 30 and a coiled spring 36 is arranged under compression between the ring 35 and the 75 ball valve 33 to urge the valve upwardly against

its seat 32. During the down stroke of the plunger 14 the valve 33 opens to allow the fluid displaced by the plunger head 19 to discharge downwardly through the plunger opening 31. During the up stroke of the plunger 14 the valve 33 is closed and the valve 27 is opened.

The means 11 is provided to releasably anchor or secure the pump means 10 in the well liner L. The anchor means 11 is preferably in the nature of a slip means. As illustrated, the means 11 includes a tubular cone 37 on the pump barrel 13. The cone 37 is secured to the exterior of the barrel 13 by welding or other suitable means and has a downwardly and inwardly tapered external surface. The means 11 further includes a set of slips 38 cooperating with the cone 37. The slips 38 have inclined inner surfaces shiftably engaged on the cone 37, and toothed outer sides for gripping the internal surface of the liner L. Tail piece means is provided to control the slips 38. This tail piece means comprises spaced rings 39 shiftable on the pump barrel 14 below the cone 37 and outwardly bowed leaf springs 40 extending between and connecting the rings 39. The springs 40 are adapted to frictionally cooperate with the internal surface of the liner L to resist movement of the tail piece assembly in the liner. Reins 41 connect the lower ends of the slips 38 with the upper tail piece ring 39.

Releasable latch means is provided for holding the slips 38 in the retracted positions so that the tool may be conveniently moved through the liner L and through the well. One or more hook-like latches 42 are secured to the upper tail piece ring 39 and are adapted to cooperate with pins 43 projecting from the barrel 13. When the latches 42 are in cooperation with the pins 43 the slips 38 are latched or held in their retracted positions where they are clear of the interior of the liner L. The pins 43 may be released from the latches by a partial turning movement of the barrel 13 followed by a downward movement of the barrel.

A releasable clutch connection is provided for transmitting turning movement from the plunger 14 to the barrel 13 to effect the release and re-engagement of the latch means 42-43 just described. This clutch means may include clutch parts or teeth 44 on the under side of the upper barrel cap 15 and complementary clutch teeth 45 on the upper end of the plug 23. When the cleaner is run into the well and when the plunger 14 is in its uppermost position with respect to the barrel 13, the teeth 44 and 45 cooperate for the transmission of turning forces so that the string S may be turned to effect the release and re-engagement of the latch means 42-43.

The packer 12 is an important feature of the invention. In the preferred construction the packer 12 is connected with the pump plunger 14 to directly receive the pumped fluid therefrom and to discharge the pumped fluid through the liner perforations P as the pump means 10 is operated. The packer 12 is spaced below the pump barrel 13 and is interposed in or secured to the plunger 14. In the form of the invention illustrated in Figs. 1 to 4, inclusive, of the drawing, the packer 12 includes a tubular carrier or nipple 46 secured to the pump plunger 14. A threaded coupling 47 serves to secure the nipple 46 to the lower end of the pump plunger 14. A similar threaded coupling 48 secures a lower valve section 49a to the lower end of the nipple 46. Collars 49 are welded or otherwise fixed to the

nipple 46 in spaced adjacent relation to the couplings 47 and 48.

The packer 12 further includes opposed cup-like sections 50 of rubber, rubber composition, synthetic rubber, or the like, arranged on the nipple 46. The packer sections 50 are arranged in opposed end to end relation with their large ends in abutment and with their tapered smaller ends facing upwardly and downwardly. The small end portions of the sections 50 are vulcanized to sleeves 51 which surround the nipple 46 between the collars 49 and the adjacent couplings 47 and 48. The opposed abutting ends of the packer sections 50 are cemented or vulcanized together so that the two sections 50, in effect, constitute a continuous packer body. The packer sections 50 are reinforced by longitudinally extending wear-taking wires 52. The wires 52 are spaced apart circumferentially and are embedded or partially embedded in the exteriors of the sections 50. The wires 52 preferably extend between the upper and lower end portions of the packer 12. The opposite ends of the wires 52 may be curved or bent inwardly to be securely anchored in the sections 50. Metal cups 53 may engage about the reduced end portions of the sections 50 to cover and retain the end parts of the wires 52. The cups 53 engage about the nipple 46 and the adjacent cups 53 and sleeves 51 are clamped between the collars 49 and the couplings 47 and 48. This effectively secures the packer 12 to the nipple 46.

The packer 12 just described is adapted to have shiftable sealing cooperation with the internal surface of the liner L. The packer 12 is proportioned so that its intermediate part is compressed or distorted to a substantially cylindrical shape through its engagement with the inner surface of the liner L. It is to be observed that the packer 12 comprising the opposed abutting sections 50 is hollow to be more readily compressed or distorted to conform to the inner wall of the liner L.

In accordance with the invention the packer 12 has a window or discharge orifice 55 for discharging the fluid pumped by the means 10. The orifice 55 is spaced between the ends of the packer 12 and is preferably equally spaced between the opposite ends of the packer. The discharge orifice 55 faces laterally or horizontally and is preferably, though not necessarily, square or rectangular in cross-sectional shape. The orifice 55 is proportioned to oppose a limited number of the spaced perforations P in the liner L. For example, it may be proportioned to oppose three or four perforations P. The abutting end portions of the packer sections 50 are shaped to provide or define the orifice 55. The sections 50 have inturned flanges 56 providing or defining the side walls of the orifice 55. The flanges 56 extend inwardly to the nipple 46 and are preferably cemented, vulcanized, or otherwise secured to the nipple in such a manner that fluid pressure cannot leak past them. The nipple 46 is tubular and being connected with the plunger 14 by the coupling 47 it has its opening in communication with the opening 31 of the plunger. The nipple 46 is ported to discharge the pumped fluid outwardly through the discharge orifice 55. In the preferred construction a plurality of spaced jetting ports 57 is provided in the wall of the nipple 46 to communicate with the orifice 55. The ports 57 are adapted to discharge or jet the pumped fluid outwardly through the orifice 55 during the down stroke of the plun-

ger 14. The orifice 55 being of small capacity allows the employment of a barrel 13 and plunger 14 of small diameter to develop high fluid pressure.

The discharge orifice 55 is spaced midway between the ends of the packer 12 so that the packer effectively seals with the internal wall of the liner L around the mouth of the orifice 55 to prevent the passage or leakage of fluid vertically or longitudinally around the packer. The wires 52 that would otherwise cross the orifice 55 may be embedded in the flanges 56 to reinforce the flanges. This construction is illustrated in Fig. 4. Longitudinal grooves 8 are preferably provided in the exterior of the packer 12 and the packer 12 may be flattened as at X, at a point diametrically opposite the orifice 55 so that the packer 12 does not have a swabbing action or piston action when reciprocated in the liner L. It is to be understood that the flattened portion 58 may be dispensed with, if desired. The grooves 8 do not join the orifice but are spaced from the orifice.

The lower section 49^a referred to above is a tubular element and has communication with the lower end of the nipple 48. The lower section 49^a is normally closed against the discharge of the pumped fluid so that the pumped fluid is obliged to discharge from the orifice 55. It may be preferred to provide a safety valve or relief valve in the lower section 49^a. In the structure illustrated this relief valve comprises a ball valve 58 normally held in its closed position by a spring 59 bearing on an adjustable plug 9. The plug 9 may be adjusted to give the valve 58 the desired setting. The valve 58 normally prevents the discharge of fluid from the lower section 49. In the event that an excessive pressure builds up in the opening 31, the nipple 46, etc., the spring 59 yields, allowing the valve 58 to open. This, of course, relieves the excess pressure. When the tool is withdrawn from the well the valve 58 is adapted to open to allow the fluid to by-pass around or past the swab element 60.

The tool may include one or more swab elements 60 for cleaning the internal surface of the liner L and for producing a swabbing action when the plunger 14 is reciprocated. In the case illustrated there is a single swab element 60. The swab element 60 is preferably spaced below the packer 12. In the construction illustrated the swab element 60 is secured to the lower section 49^a. The swab element 60 is substantially cup-shaped and is arranged with its concave side facing upwardly. The swab element 60 is expanded and active during the upstroke of the plunger 14 and operates to draw the sand, etc. into the liner L. During the downstroke of the plunger 14 when the pumped fluid is discharged from the orifice 55 the swab element 60 collapses and is substantially inactive.

Fig. 5 of the drawing illustrates a second form of packer 12^a that may be embodied in the tool of the invention. The packer 12^a includes a shouldered tubular carrier 61 connected with the plunger 14. A nipple 62 is connected with the plunger 14 by the coupling 47 and has its lower end threaded into the carrier 61. A similar nipple 63 is threaded in the carrier 61 from its lower end. The threads of the nipples 62 and 63 are preferably pitched in opposite directions. For example, the threads of the nipple 62 may be right-hand threads and the threads of the nipple 63 may be left-hand threads. The inner ends of

the nipples 62 and 63 are in tight abutting relation. The packer 12a further includes a body 64 of rubber, rubber composition, synthetic rubber, or the like, vulcanized or otherwise fixed to the carrier 61. The packer body 64 is of prolate spheroidal shape. The packer body 64 is proportioned to have its intermediate portion slidably seal with the internal surface of the liner L. The packer body 64 may be reinforced by longitudinally extending wires 65 embedded or partially embedded in its surface portion. Metal caps 66 may be arranged on the nipples 62 and 63 to engage about the opposite end portions of the body 64 and to cover the ends of the wires 65. A fluid discharge orifice 67 is provided in the packer body 64. The orifice 67 may be similar to the above described orifice 55 and continues inwardly through the carrier 61. Ports 68 are provided in the walls of the nipples 62 and 63 to discharge the pumped fluid outwardly through the orifice 67.

The operation of the improved well cleaner of the present invention is as follows: Referring now to Figs 1 to 4, inclusive, of the drawing the tool is first connected with the lower end of the string S and run into the well on the string. The slips 38 are initially in their collapsed positions and the pins 43 are in latching engagement with the latches 42. When the cleaner has been lowered to a selected position in the liner L the string S is given a partial turn and is lowered to release the pins 43 from the latches 42. The clutch parts 45 cooperate with the parts 44 for the transmission of the turning movement from the string S to the barrel 13. Following the release of the latch means 42-43 the string S is allowed to settle or to move downwardly. The resultant downward movement of the barrel 13 causes the cone 37 to actuate the slips 38 into gripping engagement with the interior of the liner L. The slips 38 operate to hold the barrel 13 and the associated parts against downward movement. The tool is then in condition for operation.

To operate the tool the string S is reciprocated so that the pump means 10 delivers fluid under pressure to the discharge orifice 55 and the element 60 has a swabbing action. During the downward strokes of the string S fluid under pressure is displaced from below the plunger head 19 to flow down through the opening 31 and the nipple 46 so that it discharges from the ports 57 and the orifice 55. The fluid under pressure discharging through the orifice 55 effectively washes or cleans the perforations P opposed or passed by the orifice 55, as the packer 12 moves downwardly. The pumped fluid is discharged in a concentrated stream at the orifice 55 to thoroughly remove the clogging accumulations from the perforations P. It will be observed that the orifice 55 discharges a downwardly moving laterally directed stream of fluid to clean the perforations P throughout a longitudinally extending band or area of the liner L. During the upstroke of the plunger 14 the valve 27 opens to admit a charge of fluid to the barrel 13 below the head 19, and the swab element 60 draws the sand and other solid matter into the liner L. The plunger 14 may be reciprocated a number of times to be sure that the several perforations P in the above mentioned band or area are thoroughly cleaned. The string S is then given a partial turn and then reciprocated so that the fluid discharged from the orifice 55 cleans the

perforations P in a longitudinally extending band or area of the liner L contiguous to the band or area first cleaned. These operations are continued until a given portion of the liner L is thoroughly cleaned, whereupon the string S may be raised to release the slips 38 and may be moved vertically to bring the tool to another position in the liner. The slips 38 may again be set or actuated and the above described operations repeated until the entire liner is thoroughly cleaned. It will be apparent that the tool may remain stationary during its operation to clean a limited selected zone of the liner L.

Having described only typical preferred forms and applications of my invention, I do not wish to be limited or restricted to the specific details herein set forth, but wish to reserve to myself any variations or modifications that may appear to those skilled in the art, or fall within the scope of the following claims.

Having described my invention, I claim:

1. In a tool for cleaning the perforations of a well liner, a packer for insertion in the liner having a fluid discharge orifice for discharging fluid outwardly through the perforations.

2. In a tool for cleaning the perforations of a well liner, a packer adapted to have sealing engagement with the interior of the liner and having a fluid discharge orifice at its zone of sealing engagement with the liner for discharging fluid outwardly through a limited number of said perforations.

3. A well cleaner for cleaning the perforations of a tubular liner comprising a fluid conducting carrier, and a packer on the carrier for shiftably sealing with the interior of the liner and having an opening receiving fluid from the carrier and discharging it through at least one perforation at the zone of engagement of the packer with the liner.

4. In a well cleaner for cleaning the perforations of a well liner, a packer of resilient sealing material adapted to have a portion in shiftable sealing engagement with the interior of the liner, the packer having an orifice for discharging fluid outwardly through certain of its perforations in the part of the liner engaged by said portion, and means for delivering fluid under pressure to said orifice.

5. In a tool for cleaning the perforations of a well liner, a packer of prolate spheroidal shape operable in the liner to have its intermediate portion in sealing engagement with the interior of the liner and having an outwardly directed opening in said portion for discharging fluid through a limited number of said perforations.

6. A tool for cleaning the perforations of a well liner comprising a packer operable in the liner to seal with its interior, the packer having an orifice for directing fluid outwardly through the perforations of the liner, and pump means connected with the packer for supplying fluid under pressure to the packer.

7. A tool for cleaning the perforations of a well liner comprising a body of packing movable in the liner and having a surface portion in sealing engagement with the inner surface of the liner, said body having an orifice discharging at said surface portion, and pump means operable in the well including two relatively reciprocable elements, one a barrel, the other a plunger, and means connecting said body with one of the said elements and delivering the pumped fluid to the orifice.

8. A tool for cleaning the perforations of a

well liner comprising a body of packing movable in the liner and having a surface portion in sealing engagement with the inner surface of the liner, said body having an orifice discharging at said surface portion, pump means operable in the well comprising two relatively reciprocable elements, one a barrel, the other a plunger, means for releasably supporting one of the pump elements in the liner, and means securing the packer body to one of the pump elements and conducting the pumped fluid to the orifice to be discharged therefrom.

9. A tool for cleaning the perforations of a well liner comprising a body of packing movable in the liner and having a surface portion in sealing engagement with the inner surface of the liner, said body having an orifice discharging at said surface portion, pump means operable in the well comprising two relatively reciprocable elements, one a barrel, the other a plunger, means for releasably supporting one of the pump elements in the liner, and means connecting the packer body with the other element to be reciprocable therewith and conducting the pumped fluid to the orifice to be discharged therefrom to clean the perforations in the path of the orifice.

10. A tool for cleaning the perforations of a well liner operable by a well string comprising, a packer operable in the liner and having a surface sealing with the wall of the well, the packer having an outwardly directed fluid discharge opening at said surface, pump means operable in the well including two relatively reciprocable elements, one a barrel, the other a plunger, means connecting the reciprocable pump element with the string to be operated thereby, means for supporting the other element in the liner releasable by turning movement of said other element, releasable clutch means for connecting said elements for transmission of turning movement whereby the string may be turned to release the supporting means, and means connecting the packer with one of the pump elements to be carried thereby and conducting the pumped fluid to the packer to be discharged from the said opening.

11. In a tool of the character described, a tubular carrier, and cup-shaped packing sections arranged on the carrier with their large ends in

opposition and abutment, the packing sections being formed to define an outwardly directed fluid discharge opening, the carrier having a port placing its interior in communication with the said opening.

12. In a tool of the character described, a tubular carrier, two substantially cup-shaped packing sections, and means securing the sections on the carrier with their large ends in abutment, the abutting end parts of the sections being shaped to define an outwardly directed fluid discharge orifice, the carrier having a port placing its interior in communication with the orifice.

13. In a tool of the character described, a tubular carrier having a lateral opening in its wall, and a body of packing on the carrier having a laterally directed fluid discharge orifice in communication with the opening.

14. In a tool of the character described, a tubular carrier having a lateral opening in its wall, a body of packing on the carrier having a laterally directed fluid discharge orifice in communication with the opening, and a fluid conducting element extending into the carrier and having ports for jetting fluid through said opening and orifice.

15. In a well cleaner for cleaning the perforations of a well liner, a packer of resilient seal material adapted to have a portion in shiftable sealing engagement with the interior of the liner, the packer having an orifice for discharging fluid outwardly through certain of the perforations in the part of the liner engaged by said portion, and means for delivering fluid under pressure to said orifice, said means comprising a tubular fluid conducting member carrying the packer and having ports for discharging jets of fluid through the orifice.

16. A tool for cleaning the perforations of a well liner comprising a packer operable in the liner to seal with its interior, the packer having an orifice for directing fluid outwardly through the perforations of the liner, a swab element connected with the packer to be in spaced relation thereto and operable in the liner to produce a swabbing action, and pump means carrying the packer and swab element and supplying fluid under pressure to the packer.

CHARLES K. HOLT.
